(57) **CLAIM**

I claim the ornamental design for a bottle, as shown and described.

DESCRIPTION

FIG. 1 is a top, front, right side perspective view of a bottle and cap showing my new design;

FIG. 2 is a top plan view thereof; and,

FIG. 3 is a front elevational view thereof, the left side, right side & rear elevational views being identical.

The broken lines shown in the drawings are for illustrative purposes only and form no part of the claimed design.
